UNITED STATES PATENT OFFICE.

HOMER L. LATIMER, OF WHITTIER, CALIFORNIA.

AUTOMATIC HOIST FOR ROTARY DRILL PIPES.

Application filed February 28, 1925. Serial No. 12,262.

To all whom it may concern:

Be it known that I, HOMER L. LATIMER, a citizen of the United States, residing at Whittier, in the county of Los Angeles and 5 State of California, have invented new and useful Improvements in Automatic Hoists for Rotary Drill Pipes, of which the following is a specification.

This invention relates to improvements in 10 hoists for drill pipe and the like in rotary drilling outfits for drilling wells.

The primary object of the invention is to provide a device adapted to be applied to a rotary drilling derrick for automatically 15 lifting a stand of pipe when it has been rotated out or separated from the string of pipe extending into the well hole.

Heretofore it has been customary to lift the string of pipe from within the well hole 20 until a stand of pipe is extending upwardly within the derrick above the rotary table. It is then customary to rotate the rotary table so as to separate the stand of pipe from the string of pipe within the well hole, 25 and as soon as the stand of pipe has been unscrewed from the string of pipe, to operate the draw-works so as to lift the stand clear of the string of pipe in the well hole. This operation of starting the draw-works 30 at the instant that the stand of pipe has been unscrewed requires a considerable amount of skill and is unsatisfactory for the reason that sometimes the draw-works is started before the stand of pipe has been 35 completely unscrewed, or the draw-works is started after the stand has been completely unscrewed, allowing the stand to ride upon the string of pipe within the well hole, damaging the threads upon the pins and 40 boxes on the pipe.

It is therefore an object of this invention to provide a device which will automatically lift the stand of pipe clear of the string of pipe within the well hole at the instant 45 that the stand of pipe is completely detached from the pipe string.

With the foregoing and other objects in view which will be made manifest in the following detailed description and pointed 50 out in the appended claims, reference is had to the accompanying drawings for an illustrative embodiment of the invention, wherein:

Figure 1 is a side elevation of a drilling 55 derrick of the rotary type, to which the improved device has been applied, the de-

vice being shown in position preparatory to separating or rotating out the stand of pipe from the pipe string in the well hole;

Fig. 2 is a view similar to Fig. 1, after 60 the stand of pipe has been separated;

Fig. 3 is a vertical section through the device providing the automatic hoist; and

Fig. 4 is a horizontal section taken substantially on the line 4—4 of Fig. 3. 65

Referring to the accompanying drawings wherein similar reference characters designate similar parts throughout, the derrick shown is of conventional construction, shown as being provided with mud sills 10 70 upon which rest cross sills 11 supporting the floor 12. The derrick cornices are shown at 13 connected by derrick girts 14 and with braces 15. The well hole is designated at 16 within which is disposed the pipe string 17. The pipe string 17 extends upwardly through the conventional rotary table R. In the illustration, the stand of pipe which is to be disconnected from the pipe string 17, is indicated at 18. The stand of pipe at its lower end is provided with a pin 19 which is threaded into the box 20 upon the pipe string 17. The upper end of the stand of pipe 18 is shown with its box 21 beneath which is disposed the elevator 22 supported by the hook 23 upon the traveling block 24. The crown block 25, which is of conventional construction, is mounted upon the top of the derrick. The conventional draw-works is also mounted upon the derrick and is illustrated at 26. The reference character 27 indicates the calf wheel with which is associated the reel 28. The line 29 has one end secured to the reel upon the draw-works and extends over the crown block 25 and beneath the traveling block 24, 85 providing a suitable number of laps extending beneath the traveling block 24 and over the crown block 25. From the crown block 25 the dead line 30 extends downwardly and is connected to the reel 28 associated with the calf wheel 27. The above described construction is conventional upon the ordinary rotary drilling rigs. 95

The invention consists of a cable section or other flexible element 31 which is detachably secured to the dead line 30 as by a clamp 32 which is located a suitable distance above the reel 28. The lower end of the flexible element or cable 31 is provided with a hook 33 adapted to be inserted in any one of the links 34 of the chain. The 100 105 110

chain composed of the links 34 is connected to an eye-bolt 35 having an eye 36 and this eye-bolt extends downwardly through a tube or cylinder 37. The lower end of the eye-bolt 35 is threaded into a cylindrical block 38, which block provides a spring seat for the coil spring 39 which is disposed within the cylinder 37 about the eye-bolt 35. The cylindrical block 38 preferably fits fairly closely within the cylinder 37, providing a free sliding fit therein. The lower end of the cylinder 37 is closed as by a screw plug 40, limiting the downward movement of the block 38. The upper end of the cylinder 37 is closed as by a threaded plug 41 having an aperture 42 therein in which is slidable the eye-bolt 35. The threaded plug 41 provides a second spring seat for the coil spring 39 against which the spring 39 is adapted to be compressed. The cylinder 37 is preferably disposed beneath the floor 12 of the derrick and is secured against one of the sills 11. As clearly shown in Figs. 3 and 4, a suitable bearing plate 43 is disposed against the side of one of the sills 11, and U-bolts 44 extend around the cylinder 37 through the bearing plate 43 and through the sill 11, so as to rigidly secure the cylinder 37 to the sill. The ends of the U-bolts 44 are provided with nuts 45 adapted to be tightened against washers 46.

The operation of the device is as follows: In pulling the drill pipe from the well hole, the drill pipe is elevated by means of the draw-works 26, winding up the line 29 and thus elevating the traveling block 24. The drill pipe is lifted a sufficient distance so that the box 20 is slightly above the rotary table R so that an elevator can be placed thereabove. As the line 29 is tightened or is wound upon the draw-works, the weight of the drill pipe creates a considerable tension upon the dead line 30. This tension tightens the cable 31 and pulls upwardly upon the eyebolt 35, compressing the spring 39 between the block 38 and the plug 41. Although the weight of the drill pipe may be tons, it will be understood that as the lower end of the dead line is fastened to the reel 28, the drill pipe will be withdrawn from the well and the dead line 30 will not move with the exception of straightening out and causing the spring 39 to be compressed. When the stand 18 has been elevated a sufficient distance, the rotary table R is then rotated so as to separate or unscrew the pin 19 from the box 20.

Heretofore, as above pointed out, it has been customary to again start the draw-works 26 at the instant that the pin 19 is separated or unscrewed from the box 20. If the draw-works 26 is started too soon, the threads sometimes become stripped, and if the draw-works 26 is started too late, the stand of pipe 18 merely rides upon the

box 20, until the draw-works is started, causing damage to the threads.

By the improved construction, the instant that the pin 19 is unscrewed from the box 20, the spring 39 expands, it being understood that the spring 39 is of sufficient strength to lift the stand 18. The expansion of the spring 39 forces the block 38 against the plug 40, pulling the eye-bolt 35 downwardly and also pulling downwardly upon the dead line 30. In this manner the stand 18 will be lifted clear of the pipe string 17 at the instant that the pin 19 is separated from the box 20, thus preventing damage to the threads upon the pin and the box. As the downward movement of the block 38 is limited by the plug 40, the stand 18 will only be lifted a certain amount, which is sufficient to lift it clear of the pipe string 17. The stand 18 can then be removed in the conventional manner and by reversing the draw-works 26, the traveling block 24 and the elevator 22 can again be lowered so that the elevator 22 can be placed beneath the box 20, preparatory to pulling a second stand of pipe from the well hole. When the stand 18 is separated from the string of pipe 17, it will be understood that the string of pipe 17 is supported by the slips upon the rotary table R. On lifting the pipe string 17, preparatory to removing the second stand of pipe, it will be understood that the dead line 30 is again tightened, taking up the slack indicated at 47, and compressing the spring 39, as before.

The hook 33 together with the links 34 provide an adjustment for the cable or flexible element 31, so that the slack 47 in the dead line 30 can be varied. If desired, the cable 31 and the improved hoisting device can be separated from the dead line 30 at any time by means of the detachable clamp 32. Although the above described device is shown as employing a spring, it is to be understood that a weight acting as a counter-balance weight could be substituted therefor, the broad idea of the invention being to supply a device capable of continually exerting a force upon the dead line on a rotary drilling derrick, which is capable of lifting a stand of pipe, this force being applied to the dead line when the draw-works 26 has stopped.

It will be understood that various changes in the detail of construction may be made without departing from the spirit and scope of the invention as defined by the appended claims.

I claim:

1. In a drilling derrick, a hoist comprising a crown block and a traveling block, a line extending over said blocks having one end secured to an object upon the derrick providing a dead line and the other end secured to a hoisting means, and means for

causing the dead line to exert a tension capable of lifting a stand of pipe after the hoisting means has ceased operation.

2. In a drilling derrick, a crown block, a traveling block, a line extending over the blocks providing a hoist, a hoisting means, one end of the line being secured to the hoisting means, the other end of the line being secured to an object upon the derrick
5 providing a dead line, an element secured to the dead line, and means for applying tension to said element capable of lifting a stand of pipe, whereby a string of pipe may be lifted by the hoisting means, and
10 a stand of pipe may be automatically lifted clear of the string upon detachment from the string without operating the hoisting means.
15 3. In a drilling derrick, a crown block, a traveling block, a line extending over the blocks to provide a hoist, a hoisting means, one end of the line being secured to the hoisting means, the other end of the line being secured to an object upon the derrick
20 providing a dead line, an element secured to the dead line, and spring means associated with said element so as to cause
25

said element to exert tension upon the dead line whereby a string of pipe may be elevated by said hoisting means and a stand 30 of pipe may be elevated by said spring means upon detachment from the string without operating the hoisting means.

4. In a drilling derrick, a crown block, a traveling block, a line extending over the blocks to provide a hoist, a hoisting means, one end of the line being secured to the hoisting means and the other end of the line being secured to an object upon the derrick providing a dead line, an element secured 40 to the dead line, a spring mounted upon the derrick, and means providing an adjustment for securing said element to said spring so as to cause said element to exert tension upon the dead line whereby a string 45 of pipe may be elevated by said hoisting means and a stand of pipe may be elevated by said spring upon detachment of the stand of pipe from the string without operating the hoisting means.

50 In testimony whereof I have signed my name to this specification.

HOMER L. LATIMER.
